UNITED STATES PATENT OFFICE.

CHARLES WEISS, OF NEW YORK, N. Y.

DESIGN FOR A PLATE OR SIMILAR ARTICLE.

Application filed January 22, 1929. Serial No. 29,731. Term of patent 7 years.

To all whom it may concern:

Be it known that I, CHARLES WEISS, a citizen of the United States, and resident of the borough of Manhattan, city, county, and State of New York, have invented a new, original and ornamental Design for a Plate or Similar Article, of which the following is a specification, reference being had to the accompanying drawing, forming part hereof, which drawing is a face view of a plate or similar article illustrating my new design, the dot and dash lined segment indicating that the design therein is to be repeated around the rim of the plate.

I claim:

The ornamental design for a plate or similar article, as shown, and described.

CHAS. WEISS.
